UNITED STATES PATENT OFFICE.

WILLIAM M. THOMAS, OF CINCINNATI, OHIO, ASSIGNOR OF ONE-HALF TO
GEORGE H. KNIGHT, OF SAME PLACE.

ELECTRO-MAGNETIC MOTOR.

SPECIFICATION forming part of Letters Patent No. 279,045, dated June 5, 1883.

Application filed January 31, 1881. (No model.)

To all whom it may concern:

Be it known that I, WILLIAM M. THOMAS, of Cincinnati, Hamilton county, Ohio, have invented new and useful Improvements in Electro-Magnetic Motors, of which the following is a specification.

My improvements relate to an arrangement of parts that is designed to secure a practically uniform, continuous, and high-dynamic effect from a given expenditure of electrical energy.

With this object in view, I employ, in association with a stationary "field-magnet," a magnetized armature of annular form which rotates in the plane of its own curvature about an axis coincident with the bisecting line of said magnet, said plane being perpendicular to that of said magnet and intersecting its poles. The magnetism of both these members is originated by enveloping electric helices, so arranged and operated as to produce in the field-magnet a constant terminal polarity, and to produce on diametrically-opposite sides of the armature a polarity which is reversed at each semi-rotation of said armature. Each of the two pole-pieces of my field-magnet is of duplex or branched form, one branch being located outside and the other inside the armature-rib. One effect of this arrangement is that as the poles of the armature during its revolution approach or recede from the respective fields, the inner branches of the field-magnet, by reason of their closer proximity to the armature-poles as said poles approach positions midway between the fields, will sooner exert and later abandon their inductive influence on the armature, and will thus prolong the magnetic energy of the field around a great part of the armature-circuit.

In the accompanying drawings, Figure 1 is a transverse section on the line x x of Fig. 2 of a motor illustrating my invention. Fig. 2 is a partly-sectional side elevation of the same. Fig. 3 is a front elevation, and Fig. 4 is a top view, the armature and terminal portions of the field-magnet being in section. In Figs. 3 and 4 the enveloping wires are shown diagrammatically, for the more ready tracing of the path of the currents. Figs. 5, 6, 7, 8, 9, and 10 show modifications of my invention.

My field-magnet has a soft-iron core, A, bent preferably into the form of the letter **U**, and supported with its two limbs in the same horizontal plane by means of posts B, whose lower extremities are attached to a suitable base, C. 55 Each extremity of my field-magnet core A takes the form of branched pole-pieces D D', having between them an interval just sufficient to receive without touching the rim of the armature, to be presently described. With the exception of the said branched extremities, both limbs of the said core are enveloped in customary helices of insulated wire for conveyance of the electric current.

Journaled in bearings E, attached to the same base, so as to be coincident with the bisecting line of the said field-magnet, is the axis or shaft F of my annular armature, of the following preferred construction: G G' are two semi-annular bars of soft iron, of oblong transverse section, attached to axis F by means of a brace, H. n' n' and s' s' are the poles or extremities of the said bars, which extremities become alternately the north and south poles at each semi-rotation of the armatures, by means and in 75 manner described in the sequel. Such change is arranged to effect both adjacent poles simultaneously and similarly, so that both of the poles here marked n' n' change to south poles at the instant that the poles here marked s' s' change to north poles.

The two bars constituting the core of my annular armature are shown separated at their poles by an insulating septum, g; but such septum may be omitted and the two bars abut directly against one another end to end, (see Fig. 8,) or the armature-core may consist of a single ring, either broken transversely, as in Fig. 9, or entire, as in Fig. 10. The wire being wrapped in the manner indicated diagrammatically in Fig. 3, so that the current flows from north on one side and toward north on the other side of the annulus, the spirality is made contrary on the two bars, so as to bring the poles of same name together. The periodical reversal of the armature-current already spoken of is effected by any suitable commutator or rheotrope. I employ for this purpose a pair of semi-cylindrical plates or segments, I I', secured concentrically to the axis F by an 100

insulating-bond, J, which bond J also serves to constitute a means of electrical insulation from each other of the segments I I'. These segments I I' are so located upon the axis as for their insulated partings to be coincident with the partings between the adjacent poles of the armature.

Attached to base C are two series of spring-plates, K K', which are so located as to press upon the remote sides of the commutator-hubs I I'. Binding-screws L L' connect by separate springs K and K' with the respective ends of wires that convey the entering and departing currents. The wire that constitutes the helix is connected by its separate extremities with the respective segments I I'. The wire P, entering the machine from the generator, is secured by binding-screw L''. From this binding-screw it passes to one pole of the field-magnet, and is wound successively around its lower limbs, till, reaching the other pole of the said field-magnet, it is conducted to the binding-screw L of the commutator. The electrical current ascending the springs K of commutator enters whichever segment I or I' happens for the time being to be in contact, and, passing thence to the corresponding extremity of the armature-wire, flows along the same in the manner shown diagrammatically in Fig. 3, whence, reaching the other extremity of the said armature-wire, it enters the other commutator-segment, and, descending the springs K', passes through binding-screw L' to wire P, by which it re-enters the battery or the other source of electrical current. The shaft F is provided with a sheave, M, or other customary transmitter of motion.

The necessity of reversal of the current of one of the members at each successive conjunction of their poles is too well known to require explanation.

Practical tests with motors constructed on this plan indicate remarkably uniform and powerful dynamic results. These results are believed to be attributable in part to the distribution of the magnetic field entirely around the circuit of the annular armature. This may be explained by the fact that when the armature has reached a position in which its poles are on a line at right angles to those of the joining line of the field-poles the inductive influence of the latter on the former is less decisively polar. In other words, there is a relaxation of magnetic tension at the armature-poles, which tension for the moment travels, so to speak, up the curve of the armature to meet the poles of the field-magnet, so as to bring the effective magnetic forces in close proximity, and to maintain a constant and approximately uniform rotative influence on the armature. The effectiveness of my motor is believed to be further in part attributable to the fact that a short rectilinear distance from pole to pole of the field-magnet, and within the effective magnetic field, is associated with a length of field-magnet measured around its

curve that secures high magnetic intensity, while the annular armature intersecting said short joining line of the field-poles permits great comparative length of armature-bar over the straight forms and relatively greater length and proximity of wrapping-wire with a corresponding increase of armature-magnetism. 70

An important beneficial effect of my form of branched pole-pieces is due to the shifting of the center of polarity from the outer to the inner branches of the field-magnet as the armature-poles approach a mid-distance between the field-poles by reason of the closer proximity of the inner branches of the field-magnet to the armature-poles at these points. The magnetic action is thus prolonged around a greater portion of the armature-circuit. 80

The above-described illustration of my invention is obviously susceptible of various modifications. For example, the armature-wire instead of being wound as in Fig. 3 may be wound as in Fig. 5. Two (or more) armatures and as many commutators may be combined on one shaft, the intersecting planes of their poles being at right angles, as shown in Fig. 6, where two armatures are employed, at angles of sixty degrees where three are employed, and so forth. Two or more such pairs may be combined with as many fixed magnets, 95 as indicated in Fig. 7. The adjacent armature-poles may or may not be magnetically insulated from one another, as already stated. The stationary and movable magnets may be provided with wholly distinct wires in connection with different batteries or generators, and when this is the case the respective currents may be of such kinds and amounts as to impart high electrical tension to the fixed magnet and electricity of quantity and tension to 105 the armature. The field-magnet core may, instead of consisting of a single bent bar, be formed of a pair of straight bars connected by a yoke in the manner familiar to constructors. 110

I am aware that both electro-dynamic machines (motors) and dynamo-electric machines (generators) have employed annular cores, either for field or armature, or both, in which the wire helices have been separated by numerous polar projections (pole-pieces) in close 115 proximity to the opposing element, as in the devices of Pacinatti and others; but I am not aware of the previous existence of such an electro-dynamic machine in which the pole-pieces have been restricted to two in number, 120 which I regard as of vital necessity where the object sought is mechanical motion of one of the elements by the electro-magnetism of the coils. Neither am I aware of the pre-existence in such machines of a branched or duplex pole-piece capable of operating alternately on the inner and outer peripheries of the armature, as in my present invention. 125

The expressions "U" and "U-formed" in this specification are intended to designate a magnet whose poles are brought near together and are presented in the same direction. 130

I claim herein as new and of my invention—

1. An electro-magnetic motor having the following elements: first, a fixed electro-magnet (field-magnet) with branched polar pieces which embrace the annular armature-rim; second, an electro-magnetized annulus (armature) with two diametrically-opposite poles capable of rotation about its geometrical axis, said axis being coincident with the line of bisection of the fixed magnet, and said rim being coincident with the poles of said magnet; third, a commutator whose plane of reversal is coincident with the poles of said annulus, the whole being constructed, combined, and adapted to operate substantially as set forth.

2. In an electro-magnetic motor, the combination, with a bi-polar annular armature re-

volving in the plane of its curvature, of a **U**-formed field-magnet whose branched pole-pieces D D' embrace the armature-rim at diametrically remote sides of the same, as and for the purposes set forth.

3. The combination, with two or more of the described field-magnets, of as many of the described armatures so attached to a single shaft as that their polar planes intersect the orbit at equal angular distances, as and for the purposes set forth.

In testimony of which invention I hereunto set my hand.

WILLIAM M. THOMAS.
